BLADE SHROUD TEMPLATE

Ernest W. Bonness, Wauwatosa, Wis., assignor to
 Allis-Chalmers Manufacturing Company, Milwaukee, Wis., a corporation of Delaware

Application March 20, 1942, Serial No. 435,483

8 Claims. (Cl. 90—62)

This invention relates generally to turbine blading and more particularly to apparatus for use in locating and forming blade tenon receiving apertures in a shroud strip adapted to be riveted, welded or otherwise secured to blades provided with tenoned ends.

In this connection, a common practice has been (1) to punch or otherwise form uniformly spaced tenon receiving holes in the shroud strip, (2) to place and hold the apertured shroud strip on the tenoned ends of the blades with the tenons projecting through the apertures therein, (3) to bring together and secure the bases or root portions of the blades in their proper row forming relation, and (4) to peen over the exposed portions of the tenons, thereby riveting the shroud strip to the tips of the blades. Another common practice has been (1) to assemble and secure the blades in their proper row forming relation, (2) to place the shroud strip on the tenoned ends of the blades and scratch or otherwise mark the shroud strip at the points the tenon receiving holes are to be formed therein, (3) to punch or otherwise form the tenon receiving holes in the shroud strip in accordance with said markings, (4) to place the apertured shroud strip on the tenoned ends of the blades with tenons projecting through the apertures therein, and (5) to peen over the exposed portions of the tenons, thereby riveting the shroud strip to the tips of the blades.

The first mentioned procedure is objectionable since the spacing of the blade bases or root portions is not absolutely uniform, i. e., variations of several thousandths of an inch are common, and as a result many blade failures are directly attributable to the initial stressing of the blades produced by the retention of the tenons in the uniformly spaced shroud apertures. The second mentioned procedure is also objectionable since errors of several thousandths of an inch occur in locating and forming the tenon receiving holes in the shroud strip and as a result the ends of some of the blades must be flexed in order to place the shroud strip on the ends of the blades with the tenons projecting through the tenon receiving holes formed in the shroud strip. Consequently, the second mentioned procedure also subjects the blades to an initial stressing action which in many instances results in blade failures during normal operation.

It is therefore an object of this invention to provide an improved apparatus which can be readily applied to the tenoned ends of a group of

positioned blades, i. e. blades assembled in a predetermined row forming relation, and which can be then readily manipulated to determine the exact spaced relation existing between the tenons on the blades in said group.

Another object of this invention is to provide an improved apparatus which accurately determines the spaced relation existing between the tenons on a group of positioned blades and which can be then applied to a shroud strip and used as a hole forming template operable to locate the tenon receiving holes in the shroud strip in exact conformity with the tenons on the blades in said group.

Still another object of this invention is to provide an improved, inexpensive apparatus which requires only a minimum degree of skill in order to locate and form the blade tenon receiving apertures in a shroud strip to be applied to a group of positioned blades having tenons thereon.

The invention accordingly consists of the various features of construction, combinations of elements, and arrangements of parts as is more fully set forth in the appended claims and in the detailed description, in which:

Fig. 1 is a side elevation of a group of positioned blades having a shroud member riveted to the tenoned ends of the blades;

Fig. 2 is a plan view of the blade group shown in Fig. 1;

Fig. 3 is a section taken on line III—III of Fig. 1;

Fig. 4 is a plan view of the preferred form of apparatus for use in locating and forming the tenon receiving apertures in a shroud member;

Fig. 5 is a partial section illustrating the apparatus shown in Fig. 4 applied to the tenoned ends of a group of positioned blades;

Fig. 6 is a partial plan view of the structure shown in Fig. 5;

Fig. 7 is a partial section taken on line VII—VII of Fig. 6;

Fig. 8 is a partial side elevation of the structure shown in Fig. 6;

Fig. 9 is a partial plan view illustrating the relative positions of the bars and tenons;

Fig. 10 is a view similar to Fig. 7 illustrating a modification in the manner of applying the apparatus to the tenoned ends of the blades;

Fig. 11 is a plan view illustrating the apparatus shown in Fig. 4 clamped against the top side of an imperforate shroud member; and

Fig. 12 is an end view of the structure shown

in Fig. 11 illustrating the use of a milling cutter for forming the tenon receiving apertures in the shroud member.

Referring to the drawing and particularly to Figs. 4-8, inclusive, it is seen that the apparatus for use in locating and forming tenon receiving apertures in a shroud member comprises an elongated flexible member or strip 1 having therein a longitudinal series of apertures 2 conforming in number and arrangement but being materially larger than the tenons 3 on the ends of the blades 4 as is clearly shown in Figs. 4-6, inclusive, and a bar 6 for each tenoned blade positionable to extend transversely across said strip and each bar having therein an opening 7 substantially conforming with the shape of a tenon as it appears in a plan view thereof. The opposite ends of each bar 6 are provided with a bore 8 which extends therethrough between pairs of raised parallel projections 9 and 11 provided on the upper and lower opposite end surface portions of each bar (see Figs. 6, 7 and 8) and a pair of blocks 12 are removably secured to the underside of the opposite ends of each bar between the projections 11 by means of cap screws 13 which extend through the bores 8 and into the internally threaded bores 14 provided in the blocks 12. Each block 12 extends inward toward the aperture 7 in the bar a considerable distance beyond the inner ends of the projections 11 (see Fig. 7) and inner marginal bottom portion of each block is recessed to provide a shroud member engaging shoulder 15. The top surface of each block is beveled as indicated by numeral 16, Fig. 8, to permit arcuate flexing of the strip 1 which has its opposite edge portions disposed between the top surfaces of the blocks 12 and the opposed underside surface portions of the bars 6 inward of the projections 11. In other words, the flexible strip 1 is held against the underside of the bars 6 with its opposite edges abutting the inner edges of the projections 11 by means of the blocks 12 which extend beneath and supportingly engage the underside marginal portions of the strip 1. The cap screws 13, when tightened, securely clamp the bars 6 to the strip 1 and, when loosened, permits the bars 6 to be selectively moved longitudinally of the strip. Stated differently, the bars 6 and strip 1 are interconnected for relative movement and when thus interconnected may be positioned as a unit on the tenoned ends of a group of positioned blades as indicated in Fig. 5.

The strip 1 and the bars 6 are preferably applied to the tenoned ends of a group of positioned blades as shown in Fig. 5 by first assembling the bars on the strip 1 with the aperture 7 in each bar overlying one of the apertures 2 in the strip 1 (see Fig. 4), then placing the assembly on the tenoned ends of the blades with the apertures 2 in the strip 1 disposed in tenon receiving relation with respect to the ends of said blades, then moving the bars relative to the strip until the aperture 7 in each bar receives the tenon on the underlying blade, and then proceeding to tighten the cap screws 13 on each bar, thereby securely clamping each bar to the strip 1 with the tenon on the underlying blade entering the aperture 7 in the overlying bar. The apertures 7 in the bars 6, although substantially conforming with the shape of a tenon as it appears in an end view thereof, are necessarily made a trifle larger than the tenons in order to permit the removal of the clamped assembly from the radially diverging tenoned ends

of a group of positioned and substantially rigid blades. In this connection, it is preferable to first position and clamp the middle bar to the strip 1 with the tenon on the underlying blade disposed centrally within the aperture 7 therein and to then alternately position and clamp the remaining bars on opposite sides of the middle bar with the tenons on the underlying blades engaging the middle bar sides of the apertures 7 in the remaining bars in the manner shown to an exaggerated degree in Fig. 9 as this procedure permits the use of apertures 7 more nearly conforming with the shape of a tenon as it appears in an end view thereof.

If the tenoned ends of a group of positioned blades can be slightly flexed, then the apertures in the bars 6 can be made in exact conformance with the shape of a tenon as it appears in an end view thereof since the clamped assembly comprising the strip 1 and bars 6 can be readily removed from the radially diverging tenoned ends of a group of positioned blades simply by appropriately flexing same. In this connection, it is preferable, in order to obtain a high degree of accuracy when using relatively thick shroud members, to correctly locate the holes or apertures in an arcuately bent shroud member with respect to the radius of curvature at its center, i. e., at a point midway between its top and bottom surfaces. This can be readily accomplished simply by spacing the underside of the extremely thin strip 1 from the ends of the blades from which the tenons project a distance approximately equal to half the thickness of the shroud member as is indicated in Fig. 10 which clearly shows such a spacing means 17 interposed between and engaging the underside of the strip 1 and the opposed end of the blade 4. This assembly can be readily applied to the tenoned ends of a group of positioned blades in the manner described in the preceding paragraph, the only difference being that the spacing means 17, depending on its nature, be placed to assume the position shown in Fig. 10 either before or after the assembly comprising the strip 1 and the bars 6 are positioned on the ends of the blades. Obviously, if said assembly is first positioned on the tenoned ends of the blades, the spacing means must be inserted before the bars 6 are immovably clamped to the strip 1.

When the bars 6 are immovably clamped to the extremely thin flexible strip 1 and the clamped assembly removed from the group of positioned blades in the manner previously described, the assembly can be then positioned on and securely clamped to a straight shroud member 18 by any suitable means such, for example, as the apparatus shown in Figs. 11 and 12 which comprises a substantially rigid, elongated table 19 including a base portion 21 provided at each end with a clamping bolt receiving slot 22 and an integral top portion 23 presenting a top surface having adjacent each side edge thereof a coextensive upstanding flange 24 and having formed therein between said flanges three coextensive recesses 26, 27 and 28 which extend in spaced parallel relation with respect to each other and with respect to the flanges 24. The recesses 26 and 28 are identical and each includes an enlarged bolt head receiving lower portion designated 29 and 31, respectively. The recess 27, which is disposed midway between the flanges 24 and midway between the recesses 26 and 28, has a central portion 32 of increased depth as is

clearly shown in Fig. 12. The width of the top portion of the recess 27 conforms with the length of the bars 6 and the preferable procedure to be followed in positioning and clamping the assembly, which comprises the relatively immovable strip 1 and the bars 6, to the shroud member 18 is to first place and hold the shroud member against the shoulders 15 presented by the inner marginal bottom portions of the blocks 12, then to place the unit comprising the assembly and the shroud member in the recess 27 (see Fig. 12), and then to securely clamp the unit to the top portion 23 of the table 19 by any suitable means such as the members 33 shown in Figs. 11 and 12. The members 33 each comprises an elongated rigid bar 34 adapted to extend across a flange 24 and the top of the cap screw 13 on the near end of the adjacent bar 6 and a bolt 36 which extends through a bore 37 in the bar 34 intermediate the ends thereof and which has a head 38 disposed in the enlarged portion 29 or 31 of the recesses 26 and 28, respectively. The bars 34 are each provided with a depending outer end portion which is adapted to engage the outside surface of a flange 24 to prevent the bar from turning when the bolt 36 is being tightened. The clamping members are assembled on the table 19 by inserting the bolt heads 38 at the ends of the recesses 26 and 28 and moving them therealong to desired positions. When the bars 34 span the flanges 24 and the cap screws 13 as shown, the tightening of the bolts 36 securely clamps the unit comprising the bars 6, strip 1 and shroud member 18 to the table 19. In this connection, the marginal recess forming the shoulder 15 on the blocks 12 should be made equal to or slightly less than the thickness of the shroud member, as shown in Fig. 12, in order to effect the necessary clamping action. Obviously, before the clamping members 33 are tightened, relative movement between the assembly, which comprises the relatively immovable strip 1 and bars 6, and the shroud member 18 should be effected when necessary to correctly position same.

The tenon receiving apertures 39 can now be readily formed in the shroud member 18 in conformance with the spacing of the tenons on the group of positioned blades simply by inserting a suitable cutting tool 41 through the aperture 7 in the bar 6 which now functions as a template to guide the cutting tool and thereby form an aperture in the underlying shroud member which conforms exactly with the aperture 7 in the bar 6. In forming the apertures 39 in the shroud member 18 with the milling type of cutter shown, either the cutting tool 41 or the table 19 may be moved in accordance with the usual practice and by any suitable means (not shown) in order to obtain exact conformance between the aperture 39 and the overlying aperture 7 in the bar 6. When the forming of the apertures 39 in the shroud member has been completed, the clamping members 33 are loosened, the assembly and shroud member removed from the table 19 and separated, and the shroud member 18 arcuately bent, by a suitable means (not shown), for positioning said member on the tenoned ends of the same group of positioned blades on which the assembly comprising the strip 1 and bars 6 were placed and rendered relatively immovable prior to their removal therefrom as previously described. Obviously, the apertured and arcuately bent shroud member can now be readily placed on the tenoned ends of said same group of positioned blades (the procedure being merely the

reverse of that specified for effecting the removal of said assembly) and the ends of the tenons peened over to produce the shrouded structure 42 shown in Figs. 1-3, inclusive.

- 5 The use of the apparatus hereinbefore described enables apertures to be formed in a shroud member in exact conformance with the spacing of the tenons on a group of positioned blades and it should therefore be obvious that a shroud member, when apertured with the aid of said apparatus, can be readily placed on and secured to the tenoned ends of said group of blades without initially stressing same. Apparatus embodying the invention is applicable to all types 10 of tenoned blades and it should be understood that the apparatus herein shown and described is solely for purposes of illustration and that it is not desired to limit the invention to the exact details of construction herein shown and described, as various modifications within the scope 15 of the appended claims may occur to persons skilled in the art.

It is claimed and desired to secure by Letters Patent:

- 25 1. Apparatus for use in locating and forming tenon receiving apertures in a shroud member for a group of positioned blades having tenons thereon comprising an apertured bar for each tenoned blade juxtaposable in tenon receiving relation to the end thereof, an elongated flexible member juxtaposable in arcuately flexed relation to the tenon ends of said blades, and means interconnecting said bars and flexible member for relative movement and for immovably securing said bars to said member.
- 30 2. Apparatus for use in locating and forming tenon receiving apertures in a shroud member for a group of positioned blades having tenons thereon comprising a bar for each tenoned blade, 35 said bars each having therein an aperture substantially conforming with the shape of a tenon as it appears in an end view thereof, an elongated flexible member juxtaposable in arcuately flexed relation to the tenon ends of said blades, and means interconnecting said bars and flexible member for relative movement and for immovably securing said bars to said member.
- 35 4. Apparatus for use in locating and forming tenon receiving apertures in a shroud member for a group of positioned blades having tenons thereon comprising a substantially rigid bar for each tenoned blade, said bars each having therein an aperture substantially conforming with the shape of a tenon as it appears in an end view thereof, an elongated flexible member juxtaposable in arcuately flexed relation to the tenon ends of said blades, and means for interconnecting said bars and flexible member to render said bars positionable in spaced relation longitudinally of said flexible member with each bar having 40 its aperture disposed in tenon receiving relation with respect to a one of said blades and to render said bars and flexible member relatively immovable.
- 45 5. Apparatus for use in locating and forming tenon receiving apertures in a shroud member for a group of positioned blades having tenons thereon comprising a substantially rigid bar for each tenoned blade, said bars each having therein an aperture substantially conforming with the shape of a tenon as it appears in an end view thereof, an elongated flexible member juxtaposable in arcuately flexed relation to the tenon ends of said blades, and means for interconnecting said bars and flexible member to render said bars positionable in spaced relation longitudinally of said flexible member with each bar having 45 its aperture disposed in tenon receiving relation with respect to a one of said blades and to render said bars and flexible member relatively immovable.
- 50 6. Apparatus for use in locating and forming tenon receiving apertures in a shroud member for a group of positioned blades having tenons thereon comprising a substantially rigid bar for each tenoned blade, said bars each having therein an aperture substantially conforming with the shape of a tenon as it appears in an end view thereof, an elongated flexible member juxtaposable in arcuately flexed relation to the tenon ends of said blades, and means for interconnecting said bars and flexible member to render said bars positionable in spaced relation longitudinally of said flexible member with each bar having 55 its aperture disposed in tenon receiving relation with respect to a one of said blades and to render said bars and flexible member relatively immovable.
- 60 7. Apparatus for use in locating and forming tenon receiving apertures in a shroud member for a group of positioned blades having tenons thereon comprising an elongated thin flexible strip juxtaposable in arcuately flexed relation to the tenon ends of said blades, a bar for each tenoned blade positionable to extend transversely of said strip and each bar having therein an aperture substantially conforming with the shape of a tenon as it appears in an end view, 65 and means for interconnecting said bars and

strip to render said bars positionable in spaced relation longitudinally of said strip with each bar having its aperture in tenon receiving relation with respect to a one of said blades and to render said bars and strip relatively immovable.

5. Apparatus for use in locating and forming tenon receiving apertures in a shroud member for a group of positioned blades having tenons thereon comprising an elongated, thin flexible base strip positionable in arcuately flexed relation on the tenon ends of said blades with a portion of each tenon projecting therebeyond, a bar for each tenoned blade positionable to extend transversely of said strip and each bar having therein an aperture substantially conforming with the shape of a tenon as it appears in an end view thereof, and means interconnecting said bars and strip for relative movement and for immovably securing said bars to said strip.

6. Apparatus for use in locating and forming tenon receiving apertures in a shroud member for a group of positioned blades having tenons thereon comprising an elongated, thin, flexible base strip positionable in arcuately flexed relation on the tenon ends of said blades with a portion of each tenon projecting therebeyond, a bar for each tenoned blade positionable to extend transversely of said strip and each bar having therein an aperture substantially conforming with the shape of a tenon as it appears in an end view thereof, and means for interconnecting said bars and strip to render same relatively movable and positionable as a unit on the tenon ends of said blades and to render said bars and strip relatively immovable.

7. Apparatus for use in locating and forming tenon receiving apertures in a shroud member for a group of positioned blades having tenons thereon comprising an elongated, thin, aper-

tured, flexible base strip positionable in arcuately flexed relation on the tenon ends of said blades with a portion of each tenon projecting there-through, a bar for each tenoned blade positionable to extend transversely of said strip and each bar having therein an aperture substantially

5 conforming with the shape of a tenon as it appears in an end view thereof, and means for interconnecting said bars and strip to render same relatively movable and positionable as a unit on the tenon ends of said blades and to render said bars and strip relatively immovable.

10 8. Apparatus for use in locating and forming tenon receiving apertures in a shroud member 15 for a group of positioned blades having tenons thereon comprising an elongated flexible strip having a thickness materially less than the length of the tenons on said blades and having therein a longitudinal series of apertures 20 forming in number and arrangement but being materially larger than the tenons on said blades, a bar for each tenoned blade positionable to extend transversely of said strip in spaced relation longitudinally of the strip and each bar having 25 therein an aperture substantially conforming with the shape of a tenon as it appears in an end view thereof, and means interconnecting said bars and strip for positioning same as a unit on the tenoned ends of said blades with each 30 aperture in said strip receiving a tenon on one of said blades and for rendering said bars and strip relatively movable to position each bar on said strip with its aperture in tenon receiving relation with respect to the tenon projecting 35 through the adjacent aperture in said strip, said interconnecting means including parts for immovably securing said bars to said strip.

ERNEST W. BONNESS.
